United States Patent Office

Des. 226,376
Patented Feb. 27, 1973

226,376

WHEEL

John A. Main, East Lansing, and Millard Fillmore Harty, Jr., Bloomfield Hills, Mich., assignors to Motor Wheel Corporation, Lansing, Mich.

Original design application Apr. 23, 1970, Ser. No. 22,592, now Patent No. 221,934. Divided and this application June 21, 1971, Ser. No. 155,398

Term of patent 14 years

Int. Cl. D12—16

U.S. Cl. D14—30 R

FIG. 1

FIG. 5

FIG. 2

FIG. 3

FIG. 4

FIG. 1 is a perspective view of a wheel as viewed from the outboard face showing our new design.

FIG. 2 is a front elevational view of the wheel of FIG. 1 but slightly enlarged thereover.

FIG. 3 is a sectional view taken on the line 3—3 of FIG. 2.

FIG. 4 is a sectional view taken on the line 4—4 of FIG. 2.

FIG. 5 is a fragmentary sectional view taken on the line 5—5 of FIG. 2.

This application is a division of our copending application Ser. No. D. 22,592 filed Apr. 23, 1970, now des. Pat. 221,934.

We claim:

The ornamental design for a wheel, substantially as shown and described.
